UNITED STATES PATENT OFFICE

135,809

DESIGN FOR A COMB CLEANER

Joseph Zuk, Chicago, Ill.

Application April 1, 1943, Serial No. 109,889

Term of patent 14 years

To all whom it may concern:

Be it known that I, Joseph Zuk, a citizen of the Union of Soviet Socialist Republics and a resident of Chicago, in the county of Cook and State of Illinois, have invented a new, original, and ornamental Design for a Comb Cleaner, of which the following is a specification, reference being had to the accompanying drawing, forming a part thereof, and in which the single figure is a perspective view of a comb cleaner, showing my new design.

I claim:

The ornamental design for a comb cleaner, as shown.

JOSEPH ZUK.
